UNITED STATES PATENT OFFICE

JAMES H. WAGENHORST, OF JACKSON, MICHIGAN

ARC LAMP

Application filed March 4, 1926. Serial No. 92,301.

My invention relates to improvements in arc lamps and has to do, more particularly, with arc lamps of the type having multiple arcs, which are burned successively.

5 The chief object of my invention is to provide an arc lamp which will burn for a long time, without requiring the replacement or renewal of the carbons. Such a lamp is particularly useful in connection with motion 10 picture studios where arc lamps are frequently used as flood lights for illuminating a set which is to be photographed. It is important, in such use, that the photographing of the set should not have to be interrupted in 15 order to permit the carbons in the lamps to be renewed, as this suspension of work keeps the set and the high salaried actors idle, and is, consequently, very expensive. It is my object to provide a lamp suitable for work 20 of this character, which can burn for a much longer time than lamps heretofore used, without requiring attention from the operator or the replacement or renewal of the carbons.

25 A further object of my invention is to provide an arc lamp, of the type having multiple arcs which burn successively, which is provided with very simple mechanism for automatically shifting successively from one arc to the other. A further object of my invention is to provide a lamp having four arcs, two of which burn simultaneously while the other pair is automatically and successively substituted for the first pair. A further object of my invention is to provide simple 30 mechanism for feeding a pair of upper electrodes toward the lower electrodes to form the arcs, which mechanism shall be particularly sensitive to changes in the resistance of the electric circuit so as to give a steady light of uniform intensity.

35 Further objects, and objects relating to details and economies of construction and operation, will definitely appear from the detailed description to follow. In one instance, I accomplish the objects of my invention by the devices and means set forth in the following specification. My invention is clearly defined and pointed out in the appended claims. A structure constituting a preferred embodiment of my invention is illustrated in

the accompanying drawings, forming a part of this specification, in which

Fig. 1 is a perspective view of a lamp embodying my invention mounted upon a suitable supporting stand, the diffusing curtain or screen being drawn across the front of the lamp. 55

Fig. 2 is a view of the lamp in front elevation, part of one cover plate being broken away. 60

Fig. 3 is a horizontal, sectional view, taken on the line 3-3 of Fig. 2. 65

Fig. 4 is a horizontal, sectional view, taken on the line 4-4 of Fig. 2.

Fig. 5 is a fragmentary view of the lamp in top elevation, parts of the cabinet being broken away in order to show the carbon feeding mechanism more clearly. 70

Fig. 6 is a vertical, sectional view through the lamp, taken on the line 6-6 of Fig. 2. 75

Fig. 7 is a detail, sectional view on line 7-7 of Fig. 2.

Fig. 8 is a detail, sectional view through a guide block for the upper electrodes, showing the feeding clutch in the position which it assumes when the circuit through the feeding solenoid is broken, and 80

Fig. 9 is a similar detail, sectional view showing the feeding clutch in the position which it assumes when the circuit through the feeding solenoid is closed.

In the drawings, the same reference numerals refer to the same part throughout the several views.

In general, I accomplish the objects of my invention by providing a pair of lower, stationary electrodes or carbons and a pair of upper electrodes or carbons clamped in a common electrode holder, so that the upper electrodes partake of simultaneous and like 85 feeding movements toward the lower electrodes and away from them, together, with a feeding mechanism by which the pair of upper electrodes is caused to move with respect to the lower electrodes, so as to draw an arc 90 between an upper and a lower electrode of the set. I propose to provide a feeding clutch acting on one of the pair of upper electrodes and a clutch-operating rod connected to the feeding clutch so as to be raised 95 100

or lowered as the circuit through a feeding solenoid is closed or broken. I propose, further, to provide a feeding lever having a solenoid core suspended from one end and co-operating with the feeding solenoid, and having the operating rod, which is connected to the feeding clutch, suspended from the other end. I propose, further, to provide two pairs of upper electrodes and co-operating lower electrodes and to provide a yoke suspended from one arm of the feeding lever with the legs of the yoke constituting the clutch-operating rods and connected to feeding clutches, one for each pair of upper electrodes.

Referring to the numbered parts of the drawings, in which I have illustrated a lamp constituting one embodiment of my invention, I have shown, in Fig. 1, a stand 10 having a fixed standard 11 upon which the movable standard 12 is vertically adjustable. The lamp is enclosed within a cabinet 13, and mounted upon the upper end of standard 12. In Fig. 1, I have shown the curtain or screen 14 drawn across the front of the lamp in order to diffuse the light coming from the arcs.

The operating parts of the lamp are all supported by the cabinet. The lower or stationary carbons or electrodes 22, are supported by a transverse angle bar 15, supported by the cabinet and extending across it from one side to the other. Mounted in this transverse brace bar 15, are four binding posts 16, the heads of which are insulated from the bar 15 by means of insulating washers 17 and 18. The two screws 16, shown at the left of Fig. 3, support the clamping members for one pair of lower electrodes, while the two screws 16, at the right support clamping members for the other pair of lower electrodes. Electrode clamping members 19 are mounted upon the binding posts 16, and clamped against the insulating washers 18, by means of nuts 20. Each of these clamping members is provided with a pair of curved recesses or notches 21, adapted to receive a pair of the lower electrodes 22. Outer clamping members 23 are mounted on the posts 16, and provided with recesses 24, fitting around the lower electrodes 22, and are clamped against the electrodes by means of the thumb nuts 25 screwed up upon the ends of the binding posts 16. The two inner posts 16, are connected electrically by the wire 26. It will thus be seen that the four lower electrodes are arranged in two pairs, all mounted upon the transverse angle bar 15 extending from one side of the cabinet to the other.

A similar transverse brace bar 27, of angle formation, extends from one side of the cabinet to the other at about the middle, and is bolted to the side walls of the cabinet. The bar 27 constitutes a support for the electrode or carbon guides 28, which are made of insulating material and are bolted to the hori-

zontal flange of the brace bar 27. There are two of these carbon guides, one for the left hand pair of upper electrodes, and the other for the right hand pair. Each of these carbon guides 28, has two holes 29 therethrough, of slightly greater diameter than the carbons which pass through and are guided in these holes. Each carbon guide also has a single hole adapted to receive the lower end of the clutch-operating rod 32, and of such diameter that this rod will move it freely. The carbons 31, of each pair of upper electrodes, are clamped between the pair of clamping members 33, 36, which are provided with notches or recesses 34, of suitable size to receive the upper ends of the carbons, and with intermediate notches 35, through which the carbon operating rod 32 may slide in order to feed the carbons. These clamping members 33, 36, are clamped against the electrodes or carbons 31, by means of the bolts 37 and thumb nuts 38. The operating rod 32, for each pair of upper electrodes, carries a feeding clutch 39, engaging one of the electrodes of the pair. This clutch has an opening therein receiving the carbon and provided with a flaring mouth 40, and with an edge 41, which is adapted to grip the carbon when the operating rod is drawn upwardly, so as to draw the upper electrodes away from the lower electrodes. This electrode feeding clutch 39 has an opening 42, through which the operating rod 32 extends, and a screw 43, carried by the rod 32, extends through an opening 44, in the clutch, that opening having sufficient clearance to permit the clutch to tilt slightly with reference to the clutch-operating rod. The feeding position of this clutch is shown in Fig. 8, in which the operating rod 32 has descended until the clutch engages the carbon guide 28 and assumes a position parallel thereto, permitting the carbon 31 to slide freely through the holes in the clutch and carbon guide. When the operating rod 32 is lifted, however, the weight of the carbon clutch causes it to tilt slightly gripping the carbon 31, so as to draw both upper carbons of the pair upwardly away from the lower carbons.

The clutch operating rods 32 are formed by the vertical legs of a yoke 45, the horizontal legs of which are embraced and clamped within a saddle 46. The yoke 45 is made in two parts and the ends of the horizontal legs are spaced from each other within saddle 46, and insulated from each other and from the saddle by a sheet of insulation 46' interposed between said horizontal leg portions and the saddle. The saddle 46 is pivoted, at 47, to the inner end of a feeding lever 48, which is fulcrumed upon a pin 52 carried by the cabinet. The lever 48 is bent back upon itself, at 49, at a point adjacent to pin 52, and then bent rearwardly and then laterally forming

the arm 51, extending to a point near the sidewall of the cabinet. This bending back of the lever, at 49, provides an extended bearing for the lever at two spaced points upon the pivot pin 52, as shown in Fig. 5.

The outer end of the arm 51 of the lever is curved, at 53, forwardly around a dash pot 58, and the upper ends of the legs of a yoke 54, are fastened to the outer end of this arm at the portion which curves around the dash-pot, as shown in Figs. 5 and 7. The lower end of this yoke 54 is bent upwardly within the dash pot, as shown in Fig. 7, and is connected to the plunger 56, having the head 57 working within the dash pot. The lower end of the stem 56 is connected by a spring 59, to the solenoid core 60, which works within the feeding solenoid 61.

One of the electrical terminals of the lamp is connected, by a wire 62, with the lower end of the solenoid 61, while the upper end of the solenoid winding is connected by a wire 63, to the combined electrode holder and guide, formed by the clamping members 33 and 36, and clamping the upper ends of the adjacent pair of upper electrodes. The corresponding electrode holder and guide for the other pair of upper electrodes is connected, by a wire 64, with the upper end of the rheostat or resistance coil 65, the lower end of which is connected by a wire 66, with the opposite terminal of the lamp.

When the circuit is closed, the current flows through the wire 62, solenoid 61, wire 63, and the electrode holder for the adjacent pair of upper electrodes to said electrodes and, through one of said electrodes, to that one of the corresponding pair of lower electrodes which is in contact with it, (see Fig. 2) and thence to the lower electrode clamps formed by the members 19 and 23. From these clamps, the current flows through the wire 26 to the corresponding clamps for the lower electrodes of the opposite set and, thence, to that upper electrode of the set, which is in contact with one of the lower electrodes, and through the combined electrode holder and guide for the upper ends of that pair of upper electrodes, and wire 64, to the rheostat 65, and then out through the wire 66, to the opposite side of the circuit in which the lamp is connected.

When the parts are in the positions shown in Fig. 2, and the circuit is closed, the solenoid 61 is energized and draws downwardly the solenoid core 60. This pulls downwardly the outer arm 51, of the feeding lever, and raises the inner arm of the lever 48, and the saddle 46 connected therewith. This raises both clutch-operating rods 32, and tilts the clutches 39, so that they grip the carbons with which they are associated and raise all the upper carbons thus drawing the arcs between the two pairs of electrodes which are shown in contact, in Fig. 2. As the

lamp burns, those carbons between which the arcs were drawn are gradually burned away and, as this tends to increase the resistance caused by the arc, the solenoid is slightly deenergized and the pull of the solenoid on the core 60 decreases slightly, so that the weight of the parts carried by the saddle 46 and the yoke 45 allows the upper electrodes to descend slightly and approach the stationary lower electrodes. Finally a point is reached at which the arcs are no longer maintained between the electrodes between which they were first drawn and the circuit is broken. Immediately, the upper electrodes descend until those upper electrodes, which were not burning during the preceding operation, contact with the corresponding lower electrodes, closing the circuit once more, and causing the solenoid to be energized, lifting the upper electrodes away from the lower electrodes, and thus drawing the arc between those electrodes which were not in use during the preceding period. This is repeated automatically from time to time and the arc shifts automatically from one set of electrodes to the other. The result is that the carbon life of this lamp is practically doubled, as the lamp can be used twice as long without replacing or renewing the carbons, as has been possible with the lamps heretofore known and used in which there are simply a pair of carbons, or two pairs of carbons forming arcs which burn simultaneously. This is a great advantage in connection with the use of these lamps in motion picture studios, as it permits the lamp to burn almost twice as long and thus avoids the necessity of suspending the photographing of a set, in order to permit the operators to trim the lamps and replace the carbons.

The yoke 45, which carries the clutch-operating rods 32, is suspended from one arm of the lever 48, and, consequently, all the movable electrodes and their operating parts are suspended from that arm of the lever. The opposite arm of the lever has a solenoid core 60 suspended therefrom and, therefore, this core tends to partially counterbalance the weight of the carbons and the connecting parts. This makes a very sensitive construction and one which responds quickly to variations in the current strength. The interposition of spring 59 between the solenoid core 60 and the yoke 54, fastened to the outer arm 51 of the feeding lever, tends to prevent the vibration of the lever and connecting parts due to minute fluctuations in the current passing through the solenoid, and the connection of the dash pot 58, and plunger 57 at this point also assists in this same purpose. A combined electrode holder and guide, comprising the clamping members 34 and 36, is accurately formed and securely clamped upon the upper ends of the movable electrodes of each pair. This combined elec-

trode holder and guide, in combination with the clutch-operating rod 32 and the clutch 39 connected to that rod and engaging one of the electrodes, serves to maintain the movable electrodes in alinement with the stationary electrodes 22 and prevents any twisting or turning of the movable electrodes with reference to the holes 29 in the insulating guide member 28 through which they extend. 5
 10 This combination of elements, therefore, prevents twisting of the electrodes and keeps them in alinement with the lower stationary electrodes without depending upon the accurate formation of the holes 29 or upon a 15 close fit between the sides of those holes and the electrodes. This is a distinct advantage as it eliminates a source of friction acting upon the movable electrodes and makes the whole mechanism more sensitive to variation 20 in current and, at the same time, insures that the electrodes shall always be in alinement with each other.

I have not described in this application the construction of the cabinet, within which 25 the lamp is housed, as that cabinet forms the subject matter of another application, filed by me of even date herewith, in which the construction of the cabinet is disclosed and claimed.

25 30 I am aware that the particular construction of arc lamp disclosed by me in this application may be changed considerably without departing from the spirit of my invention, and, therefore, I claim my invention broadly, as indicated by the appended claims.

What I claim is:

1. In an arc lamp, the combination of two pairs of stationary electrodes, two pairs of 35 movable electrodes, two electrode holders, each holder being fastened to the movable electrodes of one pair, two clutches, one co-acting with one electrode of each pair of movable electrodes, a yoke having vertical 40 legs to which said clutches are respectively connected, a pivoted lever from one arm of which said yoke is suspended, and means for rocking said lever to feed said movable electrodes with respect to the stationary electrodes. 45

2. In an arc lamp, the combination of two pairs of stationary electrodes two pairs of 50 movable electrodes, two electrode holders, each holder being fastened to one pair of 55 movable electrodes, a pair of clutches co-acting with one electrode of each of said pairs of movable electrodes, a yoke having vertical legs to which said clutches are respectively connected, a pivoted lever to which said yoke 60 is pivoted so that one pair of movable electrodes balances the other, and means for rocking said lever on its pivot to feed the movable electrodes with respect to the stationary electrodes. 65

3. In an arc lamp, the combination of two

70 pairs of stationary electrodes, two pairs of movable electrodes, electrode holders connected to the movable electrodes of each pair, a clutch for each pair of electrodes, said clutches co-operating with one electrode of each pair, a yoke having vertical legs to which said clutches are respectively connected, a pivoted lever from one arm of which said yoke is suspended, and electro-magnetic means for rocking said lever to feed the movable electrodes with respect to the stationary electrodes. 75

4. In an arc lamp, the combination of two pairs of stationary electrodes, two pairs of movable electrodes, two electrode holders 80 each electrode holder being fastened to the electrodes of one of said pairs of movable electrodes, two feeding clutches, one co-operating with an electrode of each pair of movable electrodes, a yoke having vertical legs to which said clutches are respectively connected, a pivoted lever from one arm of which said yoke is suspended, a solenoid connected in circuit with said electrodes, and a solenoid armature suspended from the other arm of 85 said lever. 90

5. In an arc lamp, the combination of a pair of electrodes connected in an electric circuit, a clutch for feeding one of said electrodes with respect to the other, a clutch-operating rod, a pivoted lever from one arm of which said rod is suspended, a fixed dash pot, the other arm of said lever being curved around said dash pot, a yoke suspended from the curved arm of said lever, a plunger connected to said yoke and working in said dash pot, a solenoid armature, a spring connecting said yoke and said armature, and a solenoid connected in the electric circuit with said electrodes and co-operating with said armature. 100

6. In an arc lamp, the combination of a pair of electrodes connected in an electric circuit, a clutch for feeding one of said electrodes with respect to the other, a clutch-operating rod, a pivoted lever from one arm of which said rod is suspended, a fixed dash pot, a yoke suspended from the other arm of said lever, a plunger connected to said yoke and working in said dash pot, a solenoid connected in circuit with said electrodes, a solenoid armature, and a spring connecting said yoke and said armature. 110

7. In an arc lamp, the combination of a pair of electrodes, connected in an electric circuit, a clutch for feeding one of said electrodes with respect to the other, a clutch-operating rod, a pivoted lever from one arm of which said rod is suspended, a fixed dash pot, a yoke suspended from the other arm of said lever, a plunger connected to said yoke and working in said dash pot, a solenoid connected in circuit with said electrodes, and a solenoid armature suspended from said yoke. 120

8. In an arc lamp, the combination of a

pair of movable electrodes, a single electrode holder fastened to both of said movable electrodes, a single feeding clutch engaging one of said movable electrodes, a clutch-operating rod connected to said clutch, and electro-magnetic means in circuit with said electrodes and controlling the movements of said rod.

9. In an arc lamp, the combination of a pair of movable electrodes, a single combined electrode holder and guide fastened to both of said movable electrodes, a single feeding clutch engaging one of said movable electrodes, a clutch-operating rod connected to said clutch and sliding in said guide, and electro-magnetic means in circuit with said electrodes for controlling the movements of said rod.

10. In an arc lamp, the combination of a pair of movable electrodes, a guide block of insulating material through which said electrodes slide, a single combined electrode holder and guide fastened to both of said movable electrodes, a feeding clutch located above said guide block and engaging one of said movable electrodes, a clutch-operating rod sliding through said holder and guide and connected to said clutch, and electro-magnetic means in circuit with said electrodes for controlling the movements of said rod.

11. In an arc lamp, the combination of two pairs of movable electrodes, two electrode holders, each of said holders being fastened to one pair of movable electrodes, a clutch co-operating with one electrode of each of said pairs of movable electrodes, a clutch-operating rod connected to each clutch, and means for actuating said clutch-operating rods.
